UNITED STATES PATENT OFFICE.

NORMAN A. REINHARD, OF ROCHESTER, NEW YORK, ASSIGNOR TO HENRY LIKLY & COMPANY, OF ROCHESTER, NEW YORK, A CORPORATION OF NEW YORK.

TRUNK.

1,330,280.

Specification of Letters Patent. Patented Feb. 10, 1920.

Application filed March 8, 1916. Serial No. 82,913.

To all whom it may concern:

Be it known that I, NORMAN A. REINHARD, of Rochester, in the county of Monroe and State of New York, have invented certain new and useful Improvements in Trunks; and I do hereby declare the following to be a full, clear, and exact description of the same, reference being had to the accompanying drawings, forming a part of this specification, and to the reference-numerals marked thereon.

My invention relates to wardrobe trunks and the like, and has for its particular object to provide an improved form of locking mechanism for a garment follower, or in other words, for the follower portion that acts, after being positioned, to hold the garments and the garment hangers tightly in their proper relation when packed, so as to prevent the garments from loosely shifting around in the trunk. A further purpose of the invention is to afford a comparatively simple structure of practical form, and one which can be readily operated in moving the parts into or out of locking relation. To these and other ends the invention consists in certain improvements and combinations of parts all as will be hereinafter more fully described, the novel features being pointed out in the claims at the end of the specification.

In the drawings:

Figure 1 is a side elevation showing the application of the invention to a usual type of wardrobe trunk with the parts shown in the position which they assume when the follower is unlocked;

Fig. 2 is a similar view with the follower locked in position;

Fig. 3 is a sectional view on line 3^a—3^a of Fig. 2;

Fig. 4 is an enlarged elevation of the locking mechanism when in the position shown in Fig. 1;

Fig. 5 is a similar view of the locking mechanism when in the position shown in Fig. 2;

Fig. 6 is a detail view showing the intermediate position of the parts of the locking mechanism as they are moved from locking to unlocking position, or vice versa, and

Fig. 7 is a sectional view on the line 7^a—7^a of Fig. 5.

Similar reference numerals in the several figures indicate the same parts.

In the illustrated embodiment of the invention, 1 designate the walls of a section of a wardrobe trunk upon which is supported a frame 2 embracing the rods 3 for carrying the usual garment hangers or forms 4, which are suspended from the rods 3, and on which the garments are arranged.

The follower employed for pressing and retaining the garments in the position in which they are packed includes side bars 5, 65 cross strips 6 and 7 and a cross rod 8 at the top, which is supported in any of the notches 9 formed in oppositely disposed bars 10 which are fixedly mounted upon the walls of the trunk. It will be seen that the follower may be adjusted to any desired position upon the supporting bars 10 by arranging the rod 8 in any selected pair of notches 9. It is necessary to afford means for holding the lower end of the follower in fixed relation in order to maintain the adjusted position of the follower, and to this end there is employed retaining means in the form of bars 11 fixedly mounted on the walls of a trunk and provided with notches 12 with which the locking means co-operates. The latter includes a locking member in the form of a rod 13 carried by a plate 14 which is slidably arranged on the follower, as will be more fully described presently. The rod 13 is movable vertically within guides 15, into and out of locking relation with the notches 12 of the retaining bars 11. The guides 15, above referred to, are carried at the lower ends of the side bars 5 of the follower, as shown best in Figs. 1 and 2, and serve to impart a regular movement to the locking member and bring it into proper locking relation with the retaining bars 11.

16 designates a plate or support carrying a flange 17 by means of which it is attached to the cross bar 7 of the follower, and 18 is a pin or bearing mounted upon the plate 16, and affording a guide for the aforesaid plate 14, which has a slot 19 engageable and movable upon the pin 18, and vertically with relation thereto. The plate 14 carries a strap 20 pivotally mounted thereon by means of the pin 21, and embodying an annular portion or ring 22 within which is arranged an eccentric 23. The latter is also pivoted upon the bearing or pin 18 and rotatable about the latter, and as the eccentric 23 is turned, it serves to cause a combined rotary and rectilinear movement of the strap 210

20, also imparting a rectilinear movement to the locking member or rod 13. 24 designates wear plates arranged on opposite sides of the eccentric 23 and the annular portion 5 of the strap 20, said wear plates being connected to the eccentric by means of a rivet 25. In order to impart movement to the eccentric, operating means is provided in the form of a rotary actuating lever or handle 10 26 pivotally mounted upon the bearing 18 and connected to the eccentric by means of the rivet 25, as shown in Fig. 7. Thus by turning the handle about the axis 18, the eccentric 23 is correspondingly moved about 15 the same axis, imparting either an up or down movement to the strap and to the locking member, according to the direction in which the handle is moved. When the handle is in the position shown in Figs. 1 and 20 4, the locking member is in its lowermost position and the follower is unlocked, whereas when the handle is turned to assume its lowermost position, as shown in Figs. 2 and 5, the locking member is moved upwardly 25 into engagement with the retaining means and the follower is locked in position.

It is desirable to provide means for holding the handle in locked position, and to this end the handle carries an abutment or lug 30 27, which engages the surface of the plate 14, as shown in Fig. 7, while the latter carries lugs or projections 28 arranged upon opposite portions of the plate to engage opposite sides of the lug 27 when the handle is 35 in its locked position, as appears clearly from an inspection of Fig. 5. The handle is sufficiently resilient to permit its being pulled away slightly from the plate 14, so as to permit the abutment 27 to clear the projections 28 when it is desired to move the handle away from the position of Fig. 5 in 40 unlocking the parts.

I claim as my invention:

1. In a trunk, the combination with an 45 adjustable garment follower, of stationary retaining means for the follower, a support therefor, locking devices including a locking member arranged on the follower for slide- 50 able movement longitudinally thereof, an eccentric pivoted on the follower and operatively connected to the locking member, and operating means connected to the eccentric.

2. In a trunk, the combination with an 55 adjustable garment follower, of stationary retaining means for the follower, a support therefor, locking devices including a locking member arranged on the follower for slide- 60 able movement longitudinally thereof, a strap pivotally arranged on the locking member, an eccentric pivoted on the follower and coöperating with the strap for controlling its position, and an operating handle associated with said eccentric.

3. In a trunk, the combination with an 65 adjustable garment follower and a support therefor, of stationary retaining means for the follower consisting of a pair of oppositely disposed notched bars, a locking member arranged on the follower comprising a rod movable into and out of engagement 70 with the aforesaid notches on said bars, an eccentric pivoted on the follower and operatively connected to the rod, and operating means connected to the eccentric.

4. In a trunk, the combination with an 75 adjustable garment follower and a support therefor, of stationary retaining means for the follower consisting of a pair of oppositely disposed notched bars, and a locking member arranged on the follower comprising 80 a rod movable into and out of engagement with the aforesaid notches on the bars, a strap pivotally arranged on the locking member, an eccentric pivoted on the follower and coöperating with the strap for 85 controlling its position, and an operating handle associated with said eccentric.

5. In a trunk, the combination with an 90 adjustable garment follower and a support therefor, of stationary retaining means for the follower consisting of a pair of oppositely disposed notched bars, a locking member arranged on the follower comprising a rod movable into and out of engagement 95 with the aforesaid notches on the bars, a strap pivotally arranged on the locking member, an eccentric pivoted on the follower and coöperating with the strap for controlling its position, an operating handle associated with said eccentric, and means co-operating with the handle to hold it in locking 100 position.

6. In a trunk, the combination with an 105 adjustable garment follower and a support therefor, of stationary retaining means for the follower consisting of a pair of oppositely disposed notched bars, a locking member arranged on the follower comprising a rod movable into and out of engagement 110 with the aforesaid notches on said bars, a plate on which the rod is mounted, a strap pivotally arranged on the locking member, an eccentric pivoted on the follower and arranged within the strap for controlling its 115 position, an operating handle associated with said eccentric, a lug or abutment formed on the handle and adapted to engage the aforementioned plate, and a pair of projections arranged on the plate between which the said lug or abutment of the handle is disposed when the handle is in locking 120 position acting to hold the parts locked.
